US00D637935S

(12) **United States Design Patent**
Levy

(10) **Patent No.:** **US D637,935 S**
(45) **Date of Patent:** **** May 17, 2011**

(54) **BEZEL**

(76) Inventor: **Rachel Levy**, Plantation, FL (US)

(**) Term: **14 Years**

(21) Appl. No.: **29/316,609**

(22) Filed: **Oct. 14, 2009**

(51) **LOC (9) Cl.** **10-07**

(52) **U.S. Cl.** **D10/128**

(58) **Field of Classification Search** **D10/128,**
D10/30-39; 368/294, 295

See application file for complete search history.

(57) **CLAIM**

The ornamental design for a bezel, as shown and described.

DESCRIPTION

FIG. 1 is a top perspective view of the present invention showing the new design.

FIG. 2 is a top plan view of the present invention shown in FIG. 1.

FIG. 3 is a bottom plan view of the present invention shown in FIG. 1.

FIG. 4 is a right side elevational view of the present invention shown in FIG. 1.

FIG. 5 is a left side elevational view of the present invention shown in FIG. 1.

FIG. 6 is a front elevational view of the present invention shown in FIG. 1; and,

FIG. 7 is a rear elevational view of the present invention shown in FIG. 1.

The trademark "SEAH" belongs to SEAH, LLC.
